Attorney.

UNITED STATES PATENT OFFICE

2,217,129

FLUID-FLOW GOVERNOR

George Mills, Gordon, New South Wales,
AustraliaApplication March 28, 1938, Serial No. 198,588
In Australia July 14, 1937

2 Claims. (Cl. 50—25)

This invention relates to improved means for controlling automatically the flow of a fluid, such as gas, water, or the like, from a service main, pipe line, or similar source of supply to a delivery pipe, and has been devised to lower the cost of production, maintenance, and renewal, and to produce governors which will function as regulators of fluid pressure and as pressure reducing valves.

10 My invention comprises a chamber provided with a flexible and approximately impervious partition wall or diaphragm, a delivery passage in constant communication with said chamber, a supply passage to the chamber and adapted to be connected with a supply main or the like source of supply, a slideable valve adapted to control discharge from the supply passage to the chamber, links connected with the valve and the flexible wall, means for preventing chattering of the valve on its seat, the provision of a relatively large discharge aperture for the supply passage, and means for detaching the operative parts of the governor as a whole from the connected supply and delivery pipes.

25 In the accompanying drawing which illustrates one form of the invention:

Fig. 1 is a part sectional side elevation of a governor;

30 Fig. 2 is a part sectional plan of the governor with the lid and diaphragm removed and with portion of the casing broken away.

A chamber is formed by an upper part casing 10 and a lower part casing 11 which parts are adapted to be secured to each other by bolts through circular flanges 12 and 13 formed on the parts. The walls of the part casing 11 are extended to form an end extension 14 of the chamber and terminate in a flange 15. A flexible wall or diaphragm 16, which is approximately impervious to the fluids treated, has its flat circular peripheral portion 17 secured in gas-tight manner between the flanges 12 and 13 and divides the chamber into separate upper and lower compartments.

45 A casting 18, adapted to be detachably bolted to the flange 15, is formed with independent supply and delivery passages 19 and 20 respectively. The supply passage 19 is tapped at 21 to take 50 a supply pipe from the source of supply and its discharge aperture is of relatively large diameter and is fitted with a bushing 22 provided with a valve seat 23. The delivery passage 20 is tapped at 24 to take a delivery pipe, which may be fitted 55 with a tap or cock, and this passage is in direct

constant communication with the interior of the lower compartment of the chamber.

A central vertical stem 25 is secured to the diaphragm base by means of relatively stiff plates 26, 27 and projects upwardly into the upper compartment where it may be provided with guides (not shown) of known construction and also projects downwardly into the lower compartment where it is forked and fitted with a transverse pin 28.

10 Metal links 29, 29 are carried loosely by the pin 28 and are pivoted on removable pins 30, 30 positioned near the seat 23. A longitudinally adjustable and longitudinally movable member 31 is loosely mounted on the pin 28 and its other 15 end contacts with the inner face of a cup 32 formed centrally on the rear face of a valve frame 33.

The front face of the valve frame is fitted with a replaceable valve plate 34 which is adapted to 20 co-operate with the valve seat 23. This frame is pressed against the member 31 by return springs 35, 35 which are mounted about guide pins 36, 36 for the frame 33.

25 A port 37 may be provided for the upper compartment for connection with a breather valve (not shown), and a port 38 for the lower compartment for connection with a relief valve (not shown).

30 A lid 39 adapted to be bolted to the upper part casing 10 permits any desired load to be placed on plate 26 so that any desired maximum pressure may be formed within the lower compartment without change of position of the valve.

35 In operation, supply and delivery pipes having been fitted to the casting 18 and the supply turned on, fluid from the supply passage 19 enters the lower compartment of the chamber and passes directly to the delivery passage and delivery pipe and at the same time tends to lift the flexible wall or diaphragm 16 and effect partial closure of the valve. Should the pressure from the supply passage increase the diaphragm is raised and by the consequent movement of the 40 links 29 and member 31 forces the valve towards its seat and thus reduces the supply of fluid to the chamber. Reduction of pressure, in similar manner, permits the springs 35 and the weight of the diaphragm and of the links to move the 45 diaphragm downwards and thus open the valve.

50 The member 31 is positioned on the pin 28 in direct line with the centre of the valve so that pressure on the supply side of the valve is transmitted directly to the pin which is retained 55

in position by the links 29. Chattering of the valve on the valve seat is thus eliminated.

I claim:

- 5 1. A fluid-flow governor comprising a casing containing a chamber and having an entrance port and an exit port, a flexible partition in said chamber, a stem connected to said partition, a valve seat at said entrance port, a valve movable to and from said seat, guide pins mounted on opposite sides of said seat, a plate carrying said valve slidable on said pins, springs on said pins urging said valve from said seat, links pivotally mounted at one end at each side of said seat and disposed at their other ends between the bifurcations of said stem and connected thereto by said transverse pin, and a member pivoted at one end on said transverse pin between said links, diverging from the plane of said links, and bearing at its other end against said plate.
- 10 15 2. A fluid-flow governor comprising a casing

containing a chamber and having an entrance port and an exit port, a flexible partition in said chamber, a stem connected with and extending from said partition and having bifurcations therebeyond, a transverse pin carried by said bifurcations, a valve seat at said entrance port, a valve movable to and from said seat, guide pins mounted on opposite sides of said seat, a plate carrying said valve slidable on said pins, springs on said pins urging said valve from its seat, links pivotally mounted at one end at each side of said seat and disposed at their other ends between the bifurcations of said stem and connected thereto by said transverse pin, and a member pivoted at one end on said transverse pin between said links, diverging from the plane of said links, and bearing at its other end against said plate.

GEORGE MILLS.
